UNITED STATES PATENT OFFICE.

JOHN PRUE KARNS, OF BOULDER, COLORADO, ASSIGNOR TO THE J. P. KARNS TUNNELING MACHINE CO., OF BOULDER, COLORADO

ANTIFRICTION-BEARING.

No. 906,496.

Specification of Letters Patent.

Patented Dec. 8, 1908.

Original application filed February 23, 1907, Serial No. 358,867. Divided and this application filed June 8, 1907.
Serial No. 377,983.

To all whom it may concern:

Be it known that I, JOHN PRUE KARNS, a citizen of the United States, residing at Boulder, in the county of Boulder and State 5 of Colorado, have invented a new and useful Antifriction-Bearing, of which the following is a specification.

This invention has reference to improvements in anti-friction bearings designed more 10 particularly for use in connection with drilling machines such as shown and described in my application No. 358,867, filed February 23, 1907, of which this case is a division. In drilling machines such as set forth in my 15 said application the structures are necessarily massive, since the work to be done by such machines is very heavy, particularly in the larger types, where the drill-head is oftentimes of such size as to produce a bore up 20 to eighteen or more feet in diameter, and is designed to work through all types of material, even the hardest rock. Likewise, the structural parts of such machines are subjected to heavy strains and shocks because 25 of the great power required and the hammer blows delivered. In such drilling machines the drill-head is carried on a suitable shaft capable of being reciprocated on its longitudinal axis and also rotated about said axis. 30 Because of the great weight of the parts, the journal bearings of such a shaft must be of ample area and at the same time should present but little resistance to the movement of the shaft either longitudinally or 35 rotatively.

It is the object of the present invention to provide anti-friction bearings which will withstand the great strains to which bearings are subjected in machines of the character referred to but at the same time offer but a minimum of resistance to the movement of the parts carried by said bearings.

The invention consists essentially in providing a number of supporting balls for the 45 shaft, each of which is seated in a suitable pocket lined with smaller balls, and each pocket is so constructed that its smaller balls are free to travel in any plane of rotation of the larger ball, whatever that plane may 50 be, without jamming or cramping, whereby

the wear is equally distributed. In addition, the invention comprises a journal bearing in which there are a number of such ball-bearings adjustably mounted to coact with the shaft.

A full understanding of the invention is best had by reference to the following description taken in connection with the accompanying drawings forming part of this specification, in which,—

Figure 1 is a cross section through a journal bearing constructed in accordance with my invention, with parts shown in elevation; Fig. 2 is a longitudinal section of the same structure; Fig. 3 is an end view; and Fig. 4 is a section, partly in elevation, of one of the anti-friction ball carriers on a larger scale than the other figures.

Referring to the drawings, there is shown a shaft 1 which may be taken as the shaft 70 supporting a suitable drill-head of a drilling machine such as set forth in my aforesaid application. This shaft may be provided with a suitable number of journal boxes, of which but one, however, is shown 75 in the drawings. This journal box is composed of a lower or supporting member 2 and an upper or cap member 3. Each half of the journal box contains a number of ball-bearing cups 4, best shown in Fig. 4, 80 though quite clearly shown, but on a smaller scale, in the other figures. These cups 4 are each composed of a cylindrical casting having a peripheral flange 5 at the upper edge and a semi-spherical, cup-shaped receptacle 85 6 for the balls constituting the ball-bearing unit. This ball-bearing is composed of a large ball 7 seated upon a number of smaller balls 8 embracing practically half the surface of the larger ball and disposed between 90 the latter and the walls of the semi-spherical receptacle 6 and constituting a lining for said receptacle or pocket. These balls are retained in the cup by a top plate 9 having an opening 10 of suitable shape to permit 95 the ball 7 to project for a distance but at the same time preventing it from leaving the pocket in which it is seated. The opening 10 through the plate 9 is slightly tapered and its smaller diameter is less than the di- 100

ameter of the ball 7, so that the latter cannot pass through this plate. When the bearing is in operative relation to the shaft there will be just sufficient clearance between the ball 7 and the walls of the opening 10 to permit the ball to turn freely without binding.

The upper edge of the receptacle 6 is enlarged by a peripheral groove 11 of such size as to permit the upper row of balls to play around the same freely, so that when the large ball 7 is rotated the smaller balls 8 are slowly carried down one side and up the other side into the free runway 11, when they will be readily diverted laterally and quickly find their way around this runway to follow the downward stream of balls passing under the large ball 7. This free runway is an important feature of these ball-bearing units, since it prevents any danger of the smaller balls jamming under the action of the large ball, and also causes the various balls 8 to be brought into action frequently, so that the wear is very evenly distributed.

Each ball cup 4 is provided with a central perforation 12, so that any particles of matter which may find their way into the receptacle 6 will ultimately escape through said passageway 12. The ball cups 4 are sometimes formed with a chamfered edge 13, and at other times the ball cups 4 are simply cylindrical, these shapes depending upon the particular point where said ball cups may be used.

The lower section 2 of the journal casing is provided with a number of cylindrical pockets 14 shaped so that they will receive the ball cups 4 and the latter are adjusted in this pocket in a radial direction with relation to the axis of the curvature thereof by adjusting screws 15 extending through the casing from the exterior thereof and bearing against the rear face of the cups 4.

In the particular machine for which these anti-friction bearings are designed the shaft 1 carries very heavy weights and there is but little tendency to lift the shaft, so that by far the greater portion of the weight and strain is borne by the lower section 2 of the journal casing. For this reason as many ball cups as can be conveniently accommodated are provided for the lower member 2 of the journal casing, and these ball cups are arranged in staggered series so as to sustain the weight at as many points as is possible without sacrificing strength. The upper half or cap plate 3 of the journal casing is provided to prevent the shaft from jumping up from its seat in the lower section 2. As the cap 3 has but little strain to bear, a single row of ball units circumferentially arranged about the shaft is sufficient for the purpose. Since, because of the

great weights carried by the journal bearings, there is more or less liability of wear, the ball-bearing units do not come into direct contact with the shaft 1 but this shaft is surrounded for a sufficient distance by a hardened steel sleeve 16, which latter, when worn, may be replaced at a trifling expense as compared with the cost of a new shaft.

It may be observed that the direct weight of the shaft is borne by the large balls 7, which may be made of ample strength for the purpose. In order to provide requisite support for these balls the small balls 8 are made to embrace a large portion of the large balls, thus distributing the weight borne by the large balls upon numerous anti-friction points.

While I have described the anti-friction bearings as particularly adapted to the drilling machine described in my aforesaid application, it will be understood that these bearings may be used in any connection where heavy moving weights are to be supported with a minimum of friction between the moving members and the bearings therefor.

I claim:—

1. A journal bearing for shafts comprising a lower section, a plurality of staggered series of ball units carried by said lower section, an upper section, and one circumferential series of ball units carried by said upper section, each journal box section having pockets for the reception of the ball units, and adjusting screws entering said pockets for moving the units radially toward the axis of the journal box.

2. A journal bearing for shafts comprising a lower section, a plurality of series of ball units carried thereby, an upper section, and one circumferential series of ball units carried thereby, each journal box section having pockets for the reception of the ball units, and means for moving the units radially with reference to the axis of the journal box.

3. A journal bearing comprising two sections and ball units, one section carrying series of ball units in staggered relation and the other section carrying a single series of ball units.

4. A journal bearing for shafts, comprising two sections and ball units each consisting of a cup having a semi-spherical recess with a lining therefor of small balls, and a large ball seated on the smaller balls, one journal bearing section carrying a plurality of series of ball units and the other journal bearing section carrying a lesser number of ball units than the first-named journal bearing section.

5. A journal bearing comprising two sections and ball units, each unit being composed of a cup formed with a semi-spherical

recess, a lining of small balls in said cup and a large ball seated on the smaller balls, one journal bearing section carrying a plurality of series of such ball units in staggered relation and the other section carrying a single circumferential series of such ball units.

In testimony that I claim the foregoing

as my own, I have hereto affixed my signature in the presence of two witnesses.

JOHN PRUE KARNS.
